H. L. BLYDENBURGH

SEDIMENT TRAP

Filed July 22, 1922

FIG 2

FIG 1

FIG 3

FIG 4

INVENTOR.

Harold L. Blydenburgh.

BY

Charles E. Hincky,
ATTORNEY.

UNITED STATES PATENT OFFICE.

HAROLD L. BLYDENBURGH, OF DETROIT, MICHIGAN.

SEDIMENT TRAP.

Application filed July 22, 1922. Serial No. 576,712.

To all whom it may concern:

Be it known that I, HAROLD L. BLYDENBURGH, a citizen of the United States, residing at Detroit, county of Wayne, State 5 of Michigan, have invented a certain new and useful Improvement in Sediment Traps, and declare the following to be a full, clear, and exact description of the same, such as will enable others skilled in the art to which 10 it pertains to make and use the same, reference being had to the accompanying drawings, which form a part of this specification.

This invention relates to sediment traps and the object of the invention is to provide 15 a device for straining fuel oil which is connected in the line through which the fuel oil is fed to the engine. A further object of the invention is to provide a straining device composed of comparatively few parts 20 and in which the screen cannot easily become clogged. Another object of the invention is to provide a sediment trap into which the oil is fed with a whirling motion to force the impurities to the outside and the oil is taken from the center and passed 25 through a screen before being discharged through the outlet. Another object of the invention is to provide a device of the character described in which the bowl may be easily removed and the sediment therein disposed of and the bowl may as easily be replaced. A still further object of the invention 30 is to provide a means whereby the screen may be easily removed for cleaning and may be also easily secured back in place. These objects and the several novel features 35 of the invention are hereinafter more fully described and claimed and the preferred form of construction by which these objects 40 are attained is shown in the accompanying drawings in which—

Fig. 1 is an elevation of the device.

Fig. 2 is a section taken on line 2—2 of Fig. 1.

Fig. 3 is a bottom view of the device, with the bowl removed.

Fig. 4 is a plan view of the device.

As shown in Fig. 1 the device comprises a base 1 having a threaded aperture 2 leading thereto as shown in Fig. 2 into which the inlet line for the oil may be threaded. Within the base 1 is a semi-cylindrical chamber 3 having a sloping upper face 4. Depending from the center of the member 1 is

a cylindrical flange 5 providing a cylindrical 55 recess 6, and an outlet conduit 7 is provided opening into the recess 6 and having threads 8 for receiving the outlet line for the oil. The base 1 is provided with an outer circular flange 9 and an inner circular flange 60 10 and a packing ring 11 is mounted in the base 1 between the flanges 9 and 10. A bowl 12 is provided having an upper rolled edge 13 or may be provided with a flat face adapted to fit about the flange 10 and engage the 65 packing ring 11 and the bottom of the bowl is raised in the center at 14 to receive the upwardly bent portion 15 of a clamp 16. The clamp consists of a single piece of U-shaped wire, shown more particularly in 70 Fig. 1, having the upwardly extending portion 15 and inturned ends 17 extending into a roller 18. As shown in Fig. 2, the ends 17 extend into the roller 18 eccentric to the axis thereof and the roller 18 is positioned on a 75 pair of lugs 19 extending upwardly from the base 1. A wire clamp handle or lever 20 is secured in the roller 18 and is adapted to seat on the member 1 as shown in Fig. 1. This clamp when in the position shown in 80 Fig. 2 holds the rolled edge 13 of the bowl in contact with the packing ring 11 and prevents leakage thereabout as will be readily understood. A small aperture 21 is provided through the flange 5 and prevents 85 the possibility of air pockets in the upper part of the semi-cylindrical chamber 3 or the cylindrical chamber 6. A screen 22 is provided having an edge seating on the flange 5 and the central portion thereof is 90 semi-spherical and extends upwardly into the chamber 6. The flange 5 is provided with an annular tapered face 23 and a spring clip 24 is secured over the end of the flange 5 and is provided with portions 26 and 27 95 engaging the tapered face 23. When this clip is secured to the tapered faces 23 the screen 22 is securely held in position on the end of the flange 5 and the tapered face 23 prevents the clip from coming loose.

In operation the device is connected in a fuel oil feed line, the oil entering the device through the conduit 2 and being discharged from the device through the conduit 7. The oil in entering the device through the aperture 2 fills the bowl and passes around through the semi-cylindrical chamber 3 and thus imparts a rotating motion to the oil

within the bowl. This rotating motion of the oil causes the sediment to travel to the outside of the bowl and paraffin or other such foreign matter floats on the surface of the oil above the screen so that it cannot clog the screen. The oil from the center of the bowl containing the least sediment passes upwardly through the screen 22 and through the chamber 6 and thence outwardly through the conduit 7 and discharge line. Should the screen become clogged with sediment the handle 20 is turned to the left of Fig. 2 thus rolling the roller 18 to bring the inturned ends 17 of the clamp 16 to the lowermost position. At this time the bowl may be removed and the sediment therein disposed of and by slipping the clip 24 off from the conical face 23 the screen may be removed and cleaned at which time the screen and clip may be put back in place and the bowl may be mounted on the portion 15 of the clamp 16. By turning the handle 20 back to the position shown in Fig. 2 the clamp 16 is raised to draw the rolled edge 13 of the bowl up tightly against the packing ring 11. It can thus be seen that the device may be easily taken apart or cleaned and may as easily be assembled again. On account of the cleanest oil being passed through the screen the screen rarely becomes clogged to such extent that it needs cleaning and in normal use it is only necessary to remove the bowl 12 after long periods of use and dispose of the sediment therein to insure a steady flow of oil free from sediment. It is also to be noted that the device will operate equally well with lubricating oil or in fact with any liquid and it is to be understood that this device is not limited to use with fuel oil only.

From the foregoing description it becomes evident that the device is very simple and efficient in operation, will not easily get out of order, may be easily assembled or taken apart, and provides a device which accomplishes the objects described.

Having thus fully described my invention, its utility and mode of operation, what I claim and desire to secure by Letters Patent of the United States is—

1. In a sediment trap, a base having an oil inlet conduit, and an oil outlet conduit in alignment and provided with a semi-cylindrical chamber and a cylindrical chamber, a depending annular flange separating the said chambers, the oil inlet conduit opening into the semi-cylindrical chamber and the oil outlet conduit opening into the upper end of the cylindrical chamber, a screen seating on the said depending flange, a spring clip securing the screen in position on the flange, a packing ring mounted in the base, a bowl having a rolled upper edge adapted to engage the packing ring and enclose the said chambers, the said chambers

being both open to the bowl, a pair of lugs on the upper side of the base, a member rotatably mounted in the said lugs, a U-shaped clamp engaging the bottom of the bowl and having inturned upper ends extending into the rotatable member eccentric to the axis thereof, and a lever for rotating the said rotatable member, the arrangement being such that oil flowing through the bowl is given a rotary motion. 75

2. In a sediment trap, a base having an oil inlet conduit and an oil outlet conduit in alignment and provided with a semi-cylindrical chamber and an open ended cylindrical chamber, a depending annular flange separating the said chambers, the oil inlet conduit opening into the semi-cylindrical chamber and the oil outlet conduit opening into the upper end of the cylindrical chamber, a screen covering the open end of the cylindrical chamber and seating on the said depending flange, a spring clip securing the screen to the flange, a packing ring mounted in the base, a bowl having an upper edge adapted to engage the packing ring and enclose the said chambers, and a clamp securing the bowl to the said base, the arrangement being such that the flow of oil into the semi-circular chamber gives the oil within the bowl a rotary motion. 90

3. In a sediment trap, a base having an oil inlet conduit and an oil outlet conduit, the said base being provided with a semi-cylindrical chamber having a sloping upper face, the oil inlet conduit opening into the said semi-cylindrical chamber, the base being further provided with a cylindrical open ended chamber provided with a depending annular flange thereabout, a screen covering the lower open end of the said cylindrical chamber, a spring clip holding the screen in position on the said flange, the outlet conduit being in communication with the said cylindrical chamber, a bowl enclosing the chambers, and a clamp securing the bowl to the base, the semi-circular and cylindrical chambers being open to the bowl. 100

4. A sediment trap comprising a base and a bowl attached thereto providing a container for liquid, the base member having an inlet and an outlet and being provided with a central cylindrical chamber open at the bottom to the bowl, a vent between the cylindrical chamber and the bowl at the upper end, a screen covering the open end of the cylindrical chamber, and means for detachably connecting the bowl to the base. 115

5. A sediment trap comprising a base adapted for the attachment of an inlet and an outlet conduit thereto, said base having a central depending hollow cylindrical portion with which the outlet conduit is connected at the top, a screen through which fluid flows to said central portion, the said base further having a chamber surrounding 120

the said depending portion with which the inlet conduit is connected, a depending flange on the said base about the said chamber therein, a bowl having an open upper end fitting over the flange, a gasket between the edge of the bowl and the base, a yoke having a loop portion extending under the

10
the said depending portion with which the bowl is connected and by means of which the bowl is detachably and forcibly supported against the gasket.

In testimony whereof, I sign this specification.

HAROLD L. BLYDENBURGH.
